UNITED STATES PATENT OFFICE.

JOHN N. GOULD, OF FREDERICKTOWN, OHIO, ASSIGNOR, BY MESNE ASSIGNMENTS, TO THE F. B. ZIEG MFG. COMPANY, OF FREDERICKTOWN, OHIO, A CORPORATION OF OHIO.

WRINGER.

Application filed May 28, 1921. Serial No. 473,272.

To all whom it may concern:

Be it known that I, JOHN N. GOULD, a citizen of the United States, residing at Fredericktown, in the county of Knox and 5 State of Ohio, have invented certain new and useful Improvements in Wringers, of which the following is a specification.

The invention relates to clothes wringers and more particularly to power driven 10 wringers used in connection with washing machines. The invention has special relation to a safety device for the quick release and separation of the rollers in case of an emergency.

15 In the ordinary type of power driven wringers there is the constant liability of injury to the operator by having a hand caught between the compression rolls and serious injury sustained before the driving 20 mechanism can be disconnected. There is also liability of damaging the wringer mechanism when clothes become wound about the rolls or bunched in too great thickness to pass between them. Safety devices heretofore used to avoid these difficulties have been generally inconvenient and uncertain in operation.

One of the objects of my invention is to provide a quick operating roller releasing 30 device in which the operating members are at all times connected so that the rollers may be released and restored to operative relation without readjustment of the parts.

Another object of the invention is to provide controlling means for the device which is prominently located and available to the 35 operator from any position about the wringer.

Another object is to provide a releasing 40 device in which the rollers may be released from compression and separated or may be restored to operative position under compression by the movement of a single control.

45 A further object is to provide a simple construction with a minimum of parts and free of obstructions to the efficient and convenient operation of the wringer.

50 Further objects and advantages will be apparent in the following detailed description of the preferred embodiment of my invention which I have illustrated in the accompanying drawings. It will be under-

stood, however, that in the appended claims I aim to cover all legitimate variations and 55 modifications of the construction illustrated herein, which are within the scope of my invention.

In the drawings, Figure 1 is a side elevation of a wringer equipped with my device. Fig. 2 is an end view showing the parts in normal position for the operation 60 of the wringer. Fig. 3 is a side elevation of a part of the releasing device as viewed on the plane of line 3-3 in Fig. 2. Fig. 4 is 65 an end view showing the upper roll released from tension and lifted free from the lower roll. Fig. 5 is a cross sectional view of the member illustrated in Fig. 3 taken on the line 5-5 in Fig. 2.

In the embodiment of my invention herein illustrated I have shown a wringer as adapted for use in a conventional construction of a mechanical washing machine. The wringer is mounted upon a swinging bracket 70 10 which carries a gear box 11 housing suitable gear mechanism adapted to drive the wringer rolls. The bracket 10 may be provided with a depending tubular extension 12 through which a drive shaft 13 may extend into the gear box for the operation of the gear mechanism. The tubular portion 12 may be adapted for pivotal mounting in a suitable support carried by the washing machine. A hand lever 14 may be provided on the upper portion of the gear box 11 for the convenient operation of conventional means controlling the engagement 80 85 of the driving mechanism actuating the wringer rolls.

90 A pair of spaced journal blocks 15 and 16 rising from the upper surface of the bracket 10 provide bearings in which are journaled the ends of the shaft 17 which carries the lower roll 18 of the wringer. The shaft 17 has a suitable driving connection at one extremity with the gear mechanism housed within the gear box 11.

95 Positioned above the bearing blocks 15 and 16 are a pair of similar swinging bearing supports 18 and 19 pivoted at 20 (Figs. 2 and 4) on one side of the wringer to lateral projections 21 formed on the sides of the bearing blocks 15 and 16. The swinging bearing supports 18 and 19 carry suitable 100 105 bearings for the ends of a second shaft 22

upon which an upper roll 23 is constructed. The supports 18 and 19 when in normal position support the upper roll immediately above and in operating relation to the lower roll, and are adapted also to swing upwardly about their pivots and carry the upper roll a substantial distance away from the lower roll.

Rigidly mounted upon the ends, respectively, of the upper and lower roll shafts 17 and 22 adjacent to the gear box 11 are a pair of gears 24 and 25 which interengage when the upper roll is in operative position upon the lower roll, and by which the upper roll is operatively driven.

To secure the rolls in normal relation with the necessary compression for the operation of the wringer I have provided releasable tension means comprising a pair of upright members 26 and 27 pivoted at their lower ends on lateral projections 28 extending from the base portion of each of the bearing blocks 15 and 16. The members 26 and 27 are preferably constructed with U-shaped cross section, opening toward the rollers to receive the projections 28 and the tensioning members hereinafter described. The upper ends of the members 26 and 27 are rigidly interconnected by a control bar 29 by which the members may be swung simultaneously about their pivots.

Pivoted in the upper end of each of the channelled members is a short post 30 having a portion of its free end spirally corrugated to receive in snug engagement therewith one end of a coiled spring 31. The opposite end of each of the springs 31 carries a similarly threaded short post 32 which is pivoted to a lateral projection 33 carried by each of the bearing supports 18 and 19. The distance between the pivot centers of the spring supports 30 and 32 is such that with the upper bearing supports 18 and 19 in normal position with the rollers in operating relation, the springs 31 are compressed by the inward movement of the channel members 26 and 27, thus effecting the necessary operating compression between the two wringer rolls.

The lateral projections 28 formed on each of the bearing blocks 15 and 16 and the lateral projections 33 formed on the upper bearing supports 18 and 19, are of relative lengths so that the pivot centers of the lower spring supports 32 are a slight distance outwardly from alignment with the pivot centers of the upper spring supports 30 and the lower pivot centers of the upright members 26 and 27. To secure the desired normal relation of the pivot centers the inward movement of the upright members is limited by abutment with the upper bearing supports, as between the projections 33 and the rear walls of the members 26 and 27. The result of this arrangement is to effect a

locking action by the compression spring tending to normally hold the parts in operating relation, and which prevents the release of the bearing members 18 and 19 carrying the upper roll otherwise than by positive movement outwardly of the upper ends of the members 26 and 27.

With the outward swinging of the latter members, by means of the control bar 29, the relatively stationary lower pivotal supports of the springs draw the springs out of their normal position within the channeled recesses in the members 26 and 27, and with the continued movement of the latter members the upper roll bearing supports are released from compression.

In the operation of the device, the rolls when apart may be positioned as illustrated in Fig. 4. The upper roll is then depressed into position either by moving the supports 19 carrying the roll or by moving the horizontal bar 29 away from the rolls so as to draw the upper roll into a position such that the pivot between the spring 31 and the support 19 crosses the line between the pivot 20 and the pivot between spring 31 and member 27. With the parts thus positioned, the roll may be held in place while the bar 29 is raised toward the machine to exert a compressing action through spring 31 to hold the roll in place. The parts will then assume the position shown in Fig. 2. It will be observed in Fig. 2 that the lower end of the spring is slightly beyond the center toward the left so that the pressure of the spring in compression tends to move the upper end of the bar 29 toward the right in Fig. 2. To open the rolls one merely moves the bar 29 to the left (Fig. 2) or away from the rolls to cause the bottom spring pivot to cross the center line of member 27 after which the force of the spring is exerted to continue motion of the bar 29 away from the machine, thereby relieving pressure on the roll automatically. Of course it will be understood that the motion of the control bar away from the rolls will continue until the spring has crossed the line between the pivot 20 and the pivot of the spring with the bracket 19. As the control bar 29 moves away from the machine the pressure on the roll diminishes until the spring reaches its completely expanded position, after which the parts can be readily raised without exerting force against the spring 31, again bringing the parts in the position shown in Fig. 4. The control bar is sufficiently elevated above the rolls so that it offers no obstruction to the ordinary use of the wringer and by reason of its location is conspicuously available to the operator from any position on either side of the wringer.

A further advantage resides in the length of the control bar which extends over the

entire length of the rolls affording added facility to the operator for quickly grasping and releasing the rolls in case of accident.

It will now be apparent that I have provided quick releasing means of a very simple and inexpensive construction which securely holds the rolls in proper operating relation under compression until it may be desired to release them and that the latter operation may be accomplished by a simple movement of a readily available control bar, which, after movement past a certain point, instantly releases the rolls for separation.

It will also be observed that the continuous engagement of the interconnected parts avoids the necessity for any adjustments or separate replacement of either the rolls or the tensioning means in releasing the rolls or in restoring them to operative relation.

20 I claim as my invention:

1. A wringer comprising a pair of supports pivotally engaged at one end and adapted to swing relatively to each other, a pair of rolls journaled intermediately of the ends of said supports respectively, a member pivoted to one of said supports having a rigid structure of U-shaped cross section forming a lateral recess, another member pivoted to the other of said supports and to said first mentioned member, and having a resilient structure, said members being swingable into one position wherein their pivot centers are in approximate alinement with said resilient member lying in said recess and tending to force said supports toward each other, and into another position wherein said pivot centers are considerably displaced out of alinement to cause the pivot between the resilient member and one support to close the line between the pivot of the two supports and the pivot of the resilient member with a U-shaped member whereby to release said supports for separation.

45 2. A wringer comprising a lower roll, a stationary support therefor, an upper roll, a swinging support therefor hinged upon said stationary support, a member pivoted on said stationary support having a rigid structure providing a lateral recess, a spiral spring, a pair of couplings permanently secured in the respective ends of said spring

and pivoted respectively upon said swinging support and the free end of said member, said spring and end couplings being adapted 55 in the movement of said member in one direction to enter said recess in approximate alinement with the pivot center of said member, thereby compressing said spring, and by the reverse movement of said member to break said alinement and relieve said compression.

3. A wringer comprising upper and lower rolls, separable upper and lower bearing supports therefor, said bearing supports 65 having lateral portions hinged together, a normally upright member pivoted on said lower support and extending above said upper support, an abutment limiting the inward movement of said member, a compression member having pivotal connection with the upper end of said upright member and with said upper bearing support oppositely of said hinged portions, said pivotal connections being normally in approximate alinement with the pivot center of said upright member slightly displaced from true alinement with said other pivotal connections thereby tending to secure said upright member in normal position.

4. A wringer comprising a lower roll, stationary end bearings for said roll, an upper roll, movable end bearings for said upper roll, a pair of swinging members pivoted respectively to each of said stationary bearings and normally extending above said upper bearings, a pair of compression members having pivotal connections respectively with the upper portions of said swinging members and said upper bearings, said compression members normally having their pivotal connections in approximate alinement with the pivot centers of said swinging members and tending to force said movable bearings toward said stationary bearings, said connections being movable out of said alinement by the outward movement of said swinging members to release said stationary bearings, and a bar rigidly connecting said swinging members operable to swing said members simultaneously.

In testimony whereof, I have hereunto set my hand.

JOHN N. GOULD.
